COMPOSITION AND PROCESS FOR DEMUL-
SIFYING CUT OILS AND THE LIKEHarold Jay Robertson, Tulsa, Okla., assignor to
Sinclair Refining Company, New York, N. Y.,
a corporation of MaineNo Drawing. Application December 12, 1934,
Serial No. 757,215

12 Claims. (Cl. 196—4)

My invention relates to the treatment of emulsions of water in oil for the purpose of separating the water therefrom.

In the operation of oil wells, in addition to the crude oil obtained, there is ordinarily produced a greater or lesser proportion of "cut oil" or "bottom settling", this being an emulsion of water or brine in the form of fine droplets dispersed through the oil which constitutes the continuous phase of the emulsion, the emulsion being more or less permanent, unless treated for the removal of the water.

It has long been known that many such cut oils may be more or less effectively resolved or separated into oil and water by the use of softening agents such as soluble soap, etc. The usually accepted theory of these emulsions and their resolution by water softening agents is that the water of the droplets is surrounded by a skin or layer containing an emulsifying agent, the precise nature of which is not clearly known, which holds the droplets in suspension in the oil; and that the water softening agent dissolving in the water or brine of the droplets neutralizes or opposes the effect of the emulsifying agent, thus freeing the water and permitting it to drop out of the oil.

Cut oils from different wells and regions vary in their stability of emulsion and many of them are but little, if at all affected by treatment with the usual water softening agents. I believe that this is due to the character of the interface or envelope between the water or brine of the droplets and the continuous oil phase, because of which the water softening agent in the case of some cut oils more readily penetrates to the water of the dispersed phase, while in the case of other cut oils access of the water softening agent to the water is opposed or altogether prevented by the character of the enveloping emulsifying agent. Whether this difference in penetrability of the interfacial layers of emulsifying agents is due to differences in chemical composition or to physical differences such as in surface tension, thickness of the interfacial layer, size of droplets, or the like, I am unable to say.

In my improved demulsifying composition I provide a reagent, in addition to the water softening agent, which appears to aid the water softening agent in penetrating the emulsifying layer or envelope or in dissipating the latter, permitting the water softening agent to obtain access to the water or brine of the droplets. Whether or not the foregoing theory correctly represents the phenomena in question, I have found in practice that by the addition of compounds of the class herein-

after mentioned to the water softening agents, the latter are rendered more effective in demulsifying the cut or oily oils and are effective in demulsifying many such cut oils which are but slightly resolved or not at all by the water softening agents in the absence of such compound. The compounds to which I have just referred as assisting the demulsifying action of water softening compounds are the alkali hydrogen sulfite addition compounds of the aldehydes and ketones. Among the more commonly known aldehydes and ketones which form alkali hydrogen sulfite addition compounds which may be used in the practice of my invention are butyl aldehyde, crotonaldehyde, aldol, benzaldehyde, furfural, acetone, methyl-ethyl ketone and methyl iso-butyl ketone, all of which are relatively inexpensive and can be readily obtained on the market. I have found that the alkali hydrogen sulfite reaction products of each and any of these aldehydes and ketones, when mixed with soap, soap and fatty materials, or other water softening compounds of the kind, produce excellent demulsifying agents, which are more efficient in treating many cut oils than the water softening agents when used alone.

In addition to the soluble soap or similar water softening agent and the above mentioned reagents for facilitating the action of the water softening agent, my improved water softening compound may contain also a fixed oil, such as castor oil.

Inasmuch as liquid reagents are more suitable for use in the field, especially where they are fed into the flow line from the well to the wash or settling tank as is now customary, I prefer to use a liquid soap in my composition such as a soap of ricinoleic acid, though the soaps of other acids may be used, and for a portion of the fatty acid soap, a rosin may be substituted. It is also preferred to use an ammonium soap, because of its superior fluidity, rather than a sodium or potassium soap, though either of the latter may be used. However, with the use of semi-solid and solid soaps, the compositions formed range from semi-solid to solid and require in most cases special means of handling at the well (but which are now well known) and also special containers, instead of the ordinary steel drums used for liquid reagents, thus causing considerable inconvenience and extra expense which is obviated by the use of a liquid composition. For like reasons, when fatty ingredients are employed, low cold test fixed oils, such as castor oil or oils from which the solid fats have been eliminated, are to be preferred. However, non-liquid as well as liquid

reagents are efficient in breaking petroleum emulsions and can be used in the practice of my invention with the proper known devices for measuring and feeding the reagent into the cut oils 5 to be treated.

The water softening agent may be prepared in any known or obvious manner. I prefer, however, the following process and preparation: The fatty acids, (and in case rosin is used to 10 make part of the soap, the rosin) are introduced into an ordinary mixing kettle. If fatty matter such as castor oil or other low cold test fixed oil is to be introduced into the compound, this also is added to the contents of the kettle, particularly as it tends to prevent a too violent reaction 15 when the alkali is added to the fatty acid. Then the alkali is slowly added with constant stirring of the mass. If, as preferred, an ammonium soap is to be formed, strong ammonium hydroxid 20 (preferably the commercial 26° Bé. aqua ammonia) is added, the mixture being cooled if necessary, as at temperatures in excess of 100 degrees F., there is considerable loss of ammonia by evaporation. The strong ammonia is used in order to 25 keep the water content of the mix as low as possible, as too much water causes a tendency to jell. If, as is sometimes desirable, the demulsifying agent when completed is to be basic, I suitably increase the amount of ammonia used above that 30 necessary merely to form the soap. Otherwise, the ammonia should be added in the quantity necessary to neutralize the acids. After the ingredients including the ammonia have been added the mixture is preferably allowed to remain quiet to insure completion of the soap reaction, usually from two to three hours or over 35 night if convenient.

The aldehyde or ketone hydrogen sulfite ingredient may be prepared in any usual or known 40 manner, but preferably as follows:

A suitable amount of sodium or other alkali bisulfite is dissolved in water to form a cold saturated solution. To this solution is then added gradually the selected ketone or aldehyde or a 45 mixture of ketones or aldehydes or of both, in amounts sufficient to react with all of the bisulfite used. If the reaction product is soluble in water, it may be desirable to add more water than stated above to keep the reaction product 50 in solution. If, however, the reaction product is insoluble or soluble with difficulty in water, as in the case of benzaldehyde alkali hydrogen sulfite, it will, of course, be precipitated and in this event the water may be removed by filtering and drying 55 and the hydrogen sulfite compound then dissolved in the soap solution in the proportion by weight desired. If the hydrogen sulfite compound is not readily soluble in the soap, its solution may be expedited by the addition of a small quantity 60 of a suitable solvent, such as commercial alcohol, to the mixture. Also, if desired, the filtration and drying steps may be omitted, and the mixture of hydrogen sulfite compound and the excess water added to the soap solution, together with 65 sufficient alcohol or other solvent, if necessary, to afford complete mixability with the soap. I have found it preferable to use sufficient aldehyde or ketone to completely combine with the sulfite salt. Excess sulfite salt in the demulsifying agent 70 seems to have a tendency to cause the emulsion to sludge down without the desired water separation, but a slight excess of aldehyde or ketone appears not to cause any harmful effect in the treatment of the emulsion.

A specific example of the preparation of the

sulfite ingredient, in this case furfural potassium hydrogen sulfite solution, is as follows:

20 parts by weight of potassium meta bi-sulfite (containing 56.4% available SO₂) in granulated form, is dissolved in 38 parts by weight of water, 5 heating slightly to get complete solution of the salt. To this solution, after cooling, is added slowly with stirring 21.8 parts by weight of furfural (technical, 97%), cooling when necessary to prevent too rapid rise in temperature. The 10 amount of furfural required is calculated from the available SO₂ in the bi-sulfite and the purity of the furfural, which latter is determined by chemical tests.

The water softening material, prepared as 15 above described, or otherwise, and the aldehyde or ketone hydrogen sulfite product prepared as above described or otherwise, are thoroughly mixed together to insure a homogeneous, substantially clear mixture of the various ingredients. 20

A specific example of a demulsifying agent embodying my invention which I have successfully used has substantially the following percentage composition:

Furfural potassium bi-sulfite	8.57
Ammonium ricinoleate	50.07
Castor oil	28.79
Water	12.13
Ammonia	0.22
Impurities	0.22

This composition was prepared in substantially the manner specifically described above, the materials used and their proportion by volume being substantially as follows:

Furfural potassium hydrogen sulfite solution (prepared as above described)	11.1
Ricinoleic acid	50.4
Aqua ammonia (26° Bé.)	8.9
Castor oil	29.6

It will be understood that the water softening composition was prepared in the manner previously described herein from the ricinoleic acid, ammonia and castor oil in the proportions given, 45 and the furfural potassium hydrogen sulfite solution prepared as described, and then added to the water softening compound in the proportion given in the above tabulation.

The amount of my demulsifying compound to 50 be used in proportion to the amount of emulsion treated varies somewhat depending upon the character of the cut oil. In various field tests on different cut oils I have used one gallon of the compound to treat from about 250 barrels of cut 55 oil to about 400 barrels of the same with excellent results. In a specific instance 1108 barrels of clear, marketable petroleum were produced from a cut oil, with no bottom sediment discernible in either the washing or settling tank with 4½ 60 gallons of the demulsifying compound, corresponding to an average of 246 barrels produced per gallon of treating agent employed, or less than one part of compound to ten thousand gallons of oil produced, though the same cut oil 65 tested with the same water softening compound but in the absence of the sulfite addition showed no substantial effect.

As previously stated, cut oils, bottom settling and the like differ considerably among themselves and I have found it desirable therefore to vary the specific proportions of ingredients given in the above tabulation. Also, in some instances the treating agent is more effective if basic in reaction, and with this in view the amount of 75

ammonia may well be increased by an amount which may range as high as 50 per cent above that necessary to saponify the acids. The amount of furfural potassium hydrogen sulfite 5 in the treating agent may also be varied in proportion to the other ingredients by an amount from one-third to double that in the tabulated formula. Also the amount of castor oil used may be varied or it may be omitted altogether, de- 10 pending on the specific character of the oil. At times it may be desirable to heat the mixture of emulsion and demulsifier, and also, especially when the oil is only slightly cut and the emulsion highly stabilized, washing with brine or water in 15 the wash tank may expedite the demulsification.

I have referred more particularly to introducing the demulsifying agent into the flow line from the well, using the known or suitable means for the purpose, but it is also possible, if preferred, 10 to use the demulsifying agent by a batch method, introducing it into a tank of cut oil with or without heating and with or without the addition of wash water, time being given to permit the brine to settle out after the mixture has been made.

25 I claim:

1. A composition for demulsifying cut oils, bottom settling and the like, comprising a soap and an aldehyde or ketone addition product of an alkali hydrogen sulfite.
2. A composition for demulsifying cut oils, bottom settling and the like, comprising a soap and an aldehyde addition product of an alkali hydrogen sulfite.
3. A composition for demulsifying cut oils, bottom settling and the like, comprising a soap and a furfural addition product of an alkali hydrogen sulfite.
4. A composition for demulsifying cut oils, bottom settling and the like, comprising a soap, and a water soluble aldehyde or ketone addition product of an alkali hydrogen sulfite.

5. A composition for demulsifying cut oils, bottom settling and the like, comprising a soap, a fixed oil and an aldehyde or ketone addition product of an alkali hydrogen sulfite.

6. A composition for demulsifying cut oils, bottom settling and the like, comprising an ammonia soap, and an aldehyde or ketone addition product of an alkali hydrogen sulfite.

7. A composition for demulsifying cut oils, bottom settling and the like, comprising furfural 10 potassium hydrogen sulfite and a soap.

8. A composition for demulsifying cut oils, bottom settling and the like, comprising an ammonia soap of ricinoleic acid and an aldehyde or ketone addition product of an alkali hydrogen 15 sulfite.

9. A composition for demulsifying cut oils, bottom settling and the like, comprising the following ingredients in substantially the proportions given:

Parts by volume	
Furfural potassium hydrogen sulfite solution	11.1
Ricinoleic acid	50.4
Aq. ammonia (26° Bé.)	8.9 25
Castor oil	29.6

10. A process for demulsifying cut oils and the like, comprising treating the oil with a soap and an aldehyde or ketone addition product of an alkali hydrogen sulfite.

11. A process for demulsifying cut oils and the like comprising treating the oil with a soluble soap and an aldehyde or ketone addition product of an alkali hydrogen sulfite.

12. A process for demulsifying cut oils and the like comprising treating the oil with a soluble soap and furfural potassium hydrogen sulfite.

HAROLD JAY ROBERTSON. 40
